UNITED STATES PATENT OFFICE.

PAUL RAYMOND SIMMONS, OF HUNTINGTON, INDIANA, ASSIGNOR TO THE SIMMONS MANUFACTURING CO., OF HUNTINGTON, INDIANA, A CORPORATION OF INDIANA.

DISH-FORMING MACHINE.

1,273,009.

Specification of Letters Patent. Patented July 16, 1918.

Application filed May 9, 1917. Serial No. 167,600.

To all whom it may concern:

Be it known that I, PAUL RAYMOND SIMMONS, a citizen of the United States, and a resident of Huntington, in the county of 5 Huntington and State of Indiana, have invented a new and Improved Dish-Forming Machine, of which the following is a full, clear, and exact description.

My invention relates to machines for 10 forming paper dishes, pie plates, and the like, and more particularly relates to means for forming the plates or dishes by first cutting a roll of paper into shapes ready to be pressed and then feeding the cut paper 15 to the forming machine to be subjected to the action of dies.

My invention is more particularly intended as an improvement on a dish-cutting mechanism, patented by me on November 19, 20 1912, No. 1,044,931, and a dish-forming machine patented by me July 27, 1915, No. 1,147,759, the last mentioned machine including waste breakers whereby the waste material between the formed dishes is 25 broken out of the sheet.

An object of the invention is to operate the dish-cutting means of the first patent referred to in unison with dish-forming means of the second patent, whereby the 30 feeding of the cut sheet to the dies, the movements of the dies, and the movements of the waste breakers will be properly timed, the whole being actuated from a prime mover.

The present invention also has for its object to improve the machine in various particulars, whereby to insure precision and positive action in the operation of the dies and waste breakers, and to provide a construction that makes for durability, and for 40 facility in assembling or adjusting the various parts.

Further objects of the invention and the advantages of the improved construction 45 will more clearly appear as the description proceeds.

Reference is to be had to the accompanying drawings forming a part of this specification in which similar reference charac-

ters indicate corresponding parts in all the 50 views, it being understood that the drawings are merely illustrative of one example of the invention.

Figure 1 is a front elevation of a machine embodying my invention, parts being broken 55 away, the view being taken as indicated by the arrows shown in connection with the line 1—1, Fig. 6.

Fig. 2 is a sectional plan view on the line 2—2, Fig. 3; 60

Fig. 3 is a longitudinal vertical section on the line 3—3, Fig. 1;

Fig. 4 is a sectional plan view on the line 4—4, Fig. 3, showing the female dies;

Fig. 5 is a sectional plan view on the line 5—5, Fig. 3, showing the male dies and the waste breakers, the view being on a reduced scale;

Fig. 6 is a side elevation of the machine;

Fig. 7 is a detail in section on the line 7—7, Fig. 1; 70

Fig. 8 is a plan view showing the cut blank.

In carrying out my invention a web, strip, or sheet A of paper or pulp stock in moist 75 or more or less green state is partially cut into round shapes B as indicated in Fig. 8, leaving approximately triangular intermediate waste portions indicated at C. To produce the blank as in Fig. 8, a cutting machine designated generally by the numeral 10 corresponds in general with my first mentioned patent, said machine including a

knife-carrying drum or roller 11 having a knife block 12 let into the peripheral surface thereof and formed with cutting knives 13 (Fig. 1), it being understood that the knives in practice are formed as described in the patent referred to for producing the disk-like members B. Associated with the 80

roller 11 is a pressure roller 14, spring pressed as described in the patented construction, the spring pressure being adjusted by screws 15. The shaft 16 of the knife roller 11 is operated as hereinafter explained, 85 in unison with the dish-forming mechanism, next described.

The dish-forming machine includes a suit-

able base 18 which in the present instance has a shelf 17 rigid therewith on which the cutting machine 10 is supported and from said base rises a U-shaped frame 19 presenting side standards. On the base plate 20 are arranged the female dies 21 above which are the male dies 22, said female dies having spring pressed plungers 23 to detach the pressed dishes, and the dies being heated and 10 otherwise generally constructed as described in my second mentioned patent. The tubular plungers 24 of the male dies 22 move in bearings 25 on a fixed plunger box 26 extending transversely between the frame 15 members 19, and said plungers receive depending rods or stems 27 on a carriage 28, said carriage sliding on frame ribs 29 in response to the movements of a pitman 30 extending from cranks 31 on a crank shaft 20 32 turning in suitable bearings at the top of the frame parts 19. Said crank shaft is driven in any suitable manner, there being in the example shown, a gear wheel 32^a on said shaft, meshing with a pinion 32^b on a 25 drive shaft 32^c, which has a belt pulley 32^d to be driven from any convenient source of power. The parts referred to correspond essentially with the construction shown in my Patent No. 1,147,759.

30 In the present construction I provide a novel connection between the carriage 28 and the die plungers 24, the connection consisting of arms 33, 34 on the plungers and carriage, respectively, and hingedly connected as at 35, there being interposed between said arms a compression spring 36. Also, between a stem 27 and a plunger 24, a slot and pin connection is established, there being a vertical slot 37 in the plunger 40 and a pin 38 on the stem 27. The tension of the spring 36 is sufficient to resist the pressure exerted on the material in forming the dishes but the construction provides flexibility, thus preventing an undesirable 45 relation of the respective dies and thereby making for durability as well as precision in the formation of the dishes.

50 The waste breakers 39 have stems or plungers 40 reciprocating in the plunger box 26 and are provided with compression springs 41 thereon, and generally are formed and operate as in my patented construction. In the present construction, however, the plungers 40 are connected in couples by strap bars or yokes 42 at the top, and each of said yokes has a friction roller 43 at the under side which, by the spring 41, is pressed against the upper side of one arm of a lever 44, fulcrumed on brackets 45 or the like on 55 the plunger box, said spring exerting its pressure at the lower end on the plunger through the medium of a collar 40^a or other suitable means. The other arm of each lever 44 is subject to a revolving cam 46, the

60 cams of the respective levers being fixed on a transverse shaft 47 turning in bearings 47^a on the plunger box or other fixed part. The shaft 47 has a drive sprocket 48 thereon about which a chain 49 passes, said chain passing also over a sprocket 50 on a stub 70 shaft 51 provided with a pinion 52 which is in mesh with a pinion 53 on the crank shaft 32. The described drive connections between the shaft 47 and the crank shaft 32 are so formed and arranged relatively to the 75 pitman 30 and carriage 28 that the dies 22 and the waste breakers 39 will be properly timed, so that the said breakers will be moved downward against the material A just as the male dies 22 start to rise.

80 It is important in the operation of the machine that the feeding of the cut blank A from the machine 10 to the dies and die breakers be properly timed and properly registered with the dies and die breakers, 85 for which reason I provide in my present construction for the positive and accurate operation of the cutting roller 11 from the crank shaft 32. On the said crank shaft 32 is a cam 54, and riding on the periphery of the cam is a roller 55 on a connecting rod 56, the lower end of which is pivoted as at 57 to a ratchet device designated generally by the numeral 58, said device having a pawl 59 compressed by a spring 60 and including a sleeve 61 adapted to turn back and forth through a limited angle about a collar 62 keyed on the shaft 16 and formed with notches or teeth 63 to be engaged by the pawl 59. By the described arrangement 90 with each revolution of the crank shaft, the dies 22 will be operated as well as the waste breakers 39, and in unison therewith the roller 11 will be turned by the connecting rod 56 to feed the cut blank A, a proper 95 distance to bring the same in proper relation to the dies and waste breakers.

100 The described ratchet feed device for the roller 11 I am enabled to apply as an attachment, simply by applying the sleeve 61 and collar 62 to the shaft 16 and applying the cam 54 to the crank shaft. Thus, without altering the essential features of the cutting machine, I insure the effective feed and timing of the cut paper to accord with the 110 operations of the dies and waste breakers.

115 I wish to state in conclusion that although the illustrated example constitutes a practical embodiment of my invention, I do not limit myself strictly to the mechanical details herein illustrated, since manifestly the same can be considerably varied without departure from the spirit of the invention as defined in the appended claims.

120 Having thus described my invention, I claim as new, and desire to secure by Letters Patent:

1. In a machine for forming dishes from

a paper sheet, reciprocating breakers for the waste material, means connecting the breakers in couples, levers to actuate the several connecting means, and means to rock 5 said levers to actuate the respective couples.

2. In a machine for forming dishes from a paper sheet, reciprocating breakers for the waste material, springs normally tending to

move the breakers in one direction, means connecting the breakers in couples, levers 10 each having an arm engaging the connecting means of the respective couples, a cam engaging the opposite arm of each lever, and means actuating said cams.

PAUL RAYMOND SIMMONS.
